UNITED STATES PATENT OFFICE.

MARY STARMER, OF NEWPORT NEWS, VIRGINIA.

BELT BUCKLE.

Application filed July 14, 1923. Serial No. 651,612.

To all whom it may concern:

Be it known that I, MARY STARMER, a citizen of the United States, residing at Newport News, in the county of Warwick and State of Virginia, have invented new and useful Improvements in Belt Buckles, of which the following is a specification.

The belt buckle of the invention is designed as a part of wearing apparel for use with waist belts for either men or women, as a connecting and fastening device for the ends of the belt, which device may be manipulated with facility and is effective in performing its required functions. In combination with the buckle of my invention I also utilize means for receiving and securing the chain bar usually worn at the end of a watch chain.

The invention consists in certain novel combinations and arrangements of parts involving the belt buckle and the adjusting buckle as will hereinafter be more fully set forth.

In the accompanying drawings I have illustrated one complete example of the physical embodiment of my invention wherein the parts are combined and arranged in accordance with the principles of my invention.

Figure 1 is a front view at the front of the belt showing the belt buckle and adjusting buckle in their proper relation.

Figure 2 is a view similar to Figure 1 at the reverse or inner side of the belt.

Figure 3 is a horizontal sectional view of the belt buckle and adjusting buckle with the belt ends in secured position.

Figure 4 is an enlarged, detail, horizontal sectional view of a portion of the belt buckle.

Figure 5 is a vertical sectional view of a portion of the belt buckle.

Figure 6 is a detail perspective view of the adjusting buckle for the belt.

The belt, of which the two ends A and B are illustrated, may be of leather, fabric or other suitable material, and preferably is provided with an eyelet near each of its looped ends as indicated at A' and B' for securing the parts of the fastening devices. The belt buckle 1 is shown as of rectangular shape and is stamped or otherwise fashioned from sheet metal, with a top flange 2 and a bottom flange 3 extending longitudinally throughout its length and at the rear or inner side thereof.

Near one end of the buckle a pair of complementary bosses 4 and 4' are fashioned, as by stamping, in the flanges 2 and 3, and these bosses project toward the longitudinal center of the buckle to afford bearings for a wire loop 5 to which the belt end A is attached and which holds this looped or folded end of the belt flat while in use. The wire loop is of rectangular shape and is positioned at the rear of the buckle within the upper and lower flanges 2 and 3 to anchor the end A of the belt. As shown in Figs. 2 and 3 the end of the belt is folded after being passed through the loop, and the folded extremity of the belt is secured to the loop by slipping the eye A' over a prong 6 located at the approximate center of the inner bar of the rectangular loop.

At its upper and lower ends the loop is fashioned with alined coils or rings 7 and 7' which are slipped over the respective bosses 4 and 4' in the buckle flanges for the purpose of retaining the loop in position at the rear of the buckle. The bearings afforded the loop by these bosses and coils, which latter form sockets, allow a slight oscillating movement of the loop in order that it may be properly adjusted to retain the end A of the belt and with this end lie snugly within the buckle.

At the end of the buckle opposite to this loop is fashioned a longitudinally extending spring tongue or hook 8 which may be fashioned from the material of the buckle and is spaced therefrom to permit connection of the fastening link 9 carried at the end B of the belt. The fastening hook 8 and fastening link 9 may be of any suitable shape, but they are here shown rectangular to insure a stable connection, and the hook may be fashioned with an offset groove 8' for the retention of the fastening link 9.

By utilizing a single piece of wire and the proper machine tools the link is fashioned as an integral part of the larger attaching link 10 to which the looped and folded end B of the belt is attached, and an integral shank 11 formed from the ends of the wire constituting these two links, is located between the looped belt end. The fastening link and the attaching link are concealed at the back of the buckle, while the shank which is located between the looped part of the belt is also concealed and affords a finger hold for the belt end B when the latter is being connected or fastened to the buckle 1.

The buckle at its rear side is provided with an upwardly projecting tongue 12, which rises from the bottom flange 3 to a suitable height for the purpose of forming a retaining device, and at the side of this tongue a vertically disposed slot 13 is provided between the tongue and a flat back plate 14 of the buckle, the flat plate as noted rising from the edge of the flange 3. These parts are for the accommodation of the chain bar 15 and watch-chain 16 of the wearer of the belt and as will be evident from an inspection of Fig. 2 are designed to support the chain and securely hold the chair bar, both of which are indicated by dotted lines. The bar is slipped between the tongue 12 and plate 14 at one side and the body of the buckle at the other side and rests securely within the parts on the bottom flange 3 with the chain 16 suspended through the bottom of the slot 13. In the absence of the bar 15 from the chain the usual spring-ring carried in lieu thereof on the chain may be suspended from the hole or opening 17 near the upper edge of the plate 14 at the rear of the buckle, and in either event the suspending parts of the chain are concealed from view at the back of the buckle and securely fastened to the buckle.

In connection with the end B of the belt I utilize an adjusting buckle indicated as a whole by the numeral 18 which is made up in suitable manner from a metal plate and provided with top and bottom flanges 19 and 20 which may be grasped between the thumb and fingers for sliding the adjusting buckle along the belt to shorten or lengthen the latter. The end B of the belt is passed through a rectangular shaped wire loop 21 and then passed through the attaching link 10, after which the extremity of the belt end is again passed through the loop 21 and the eyelet B' of the belt is slipped over a prong 22 on this loop 21, to anchor the folded and looped end B of the belt.

Wire loop 21 is vertically disposed between the two flanges 19 and 20 of the adjusting buckle 18 and is hinged or pivoted

in a sleeve 23 fashioned at one side of the adjusting buckle in order that the folds of the looped belt end may lie flat within the adjusting buckle. To hold the buckle 18 in adjusted position on the belt I utilize a toothed jaw 24, preferably made integral with the sleeve 23 of the buckle 18, and it will be apparent from Figure 3 of the drawings that this toothed jaw engages the outer or front face of the belt where it enters the adjusting buckle and by impingement frictionally holds the buckle against slipping on the belt. In this manner the looped and folded end of the belt at B is retained against slipping within the adjusting buckle and the length of the belt is properly maintained. As is the case with the belt buckle, the operative parts of the adjusting buckle are concealed behind the latter buckle, and as seen in Figure 1 the buckles and belt present a neat appearance capable of proper ornamentation for the well groomed person.

The belt buckle and the adjusting buckle may readily be detached from one belt and attached to another belt when desired thus adapting them for use with different dresses or different suits of clothes, and the belt ends, through the instrumentality of the fastening hook and fastening link may with facility be connected or coupled, and disengaged as desired.

Having thus fully described my invention, what I claim as new and desire to secure by Letters Patent is—

1. The combination with a belt buckle having upper and lower flanges and alined bosses thereon, of a hinged fastening loop, for a belt end, having sockets complementary to said bosses, and means on said loop for engaging an eyelet in the folded belt end.

2. The combination with a belt buckle having upper and lower flanges and alined bosses thereon, of a rectangular wire-loop having coils forming complementary sockets for said bosses, and a prong on said wire-loop for engaging an eyelet on a folded belt end.

MARY STARMER.
